UNITED STATES PATENT OFFICE.

JULIUS SPIEGEL, OF NEW YORK, N. Y.

BOOKKEEPING-FORM.

1,291,223.

Specification of Letters Patent. Patented Jan. 22, 1913.

Application filed October 13, 1917. Serial No. 197,177.

To all whom it may concern:

Be it known that I, JULIUS SPIEGEL, a subject of Austria, and resident of the borough of Manhattan, in the city, county, and State of New York, have invented certain new and useful Improvements in Bookkeeping-Forms, of which the following is a specification.

The present invention relates to an improved bookkeeping form, and has for an object to provide a form which will enable a complete record of the financial transactions of a business to be made, will be simple in operation, and will insure accuracy. More particularly the embodiment of the invention disclosed herein has for its object to provide a single control sheet upon which all of the transactions of the business will be entered under debtor and creditor columns, so that the same always balances, and which permits of the determining at a glance of the condition of any feature of the business, at any time of the month, and which greatly simplifies the balancing of the books at the end of the month. A further object is to dispense with the posting of all items except "bills payable" and "bills receivable." Other objects are to provide a summarized monthly record of the condition of each feature of the business, and also a voucher record of every transaction. With my improved form, I propose to enable any one, whether an experienced bookkeeper or not, with very little instruction and practice, to keep books accurately and with a minimum consumption of time.

With these and other objects in view, an embodiment of my invention is shown in the accompanying drawings, and this embodiment will be hereinafter more fully described with reference thereto, and the invention will be finally pointed out in the claims.

In the accompanying drawings.

Figure 1 is a plan view of the "Cash journal" or control sheet, of the present embodiment of my invention;

Fig. 2 shows a sample page of the "Accounts receivable ledger";

Fig. 3 shows a sample page of the "Accounts payable ledger";

Fig. 4 is a plan view of the general ledger sheet;

Figs. 5 and 6 show samples of the vouchers employed; and

Fig. 7 shows the manner of computing a trial balance.

Similar reference characters indicate corresponding parts throughout the several figures of the drawings.

Referring to Fig. 1 of the drawings, the control sheet 10 of the present embodiment of my invention, which I have headed "Cash journal" comprises a plurality of vertical columns and a plurality of horizontal divisions which may be of any suitable dimensions to contain the data hereinafter referred to.

The uppermost division contains the headings as "Voucher," "Journal entries," "Ledger postings," etc., of the major columns formed by the heavy division lines 11.

Each major column with the exception of the "Voucher" column is divided into debtor and creditor columns by a division line 12, these columns being indicated by the abbreviations "Dr." and "Cr." provided as at 13 in the horizontal division 14 beneath the headings.

Below the division 14, the sheet is provided with a series of horizontal spaced rulings 15, upon each of which a transaction is to be entered, as hereinafter pointed out. By pre-arrangement there may be sufficient of these rulings 15 on a single sheet to contain all of the financial transactions of the business, or the same may be entered upon another continuation sheet. The spaces formed by the rulings are correspondingly and consecutively numbered at each end of the sheet as at 16 and 17, the number 16 at the left, in addition to numbering the spaces, being a voucher number, while the number 17 at the right insures the entries being placed in the proper spaces without the necessity of employing a ruler or other such guide means. The voucher column also contains two vertical divisions 18 and 19, for containing the date of the voucher and transaction.

The "Ledger postings" column is provided at its right hand end with a vertical column 20, headed by the abbreviation "L. F." as at 21, and which is adapted to receive the numbers of the ledger folios in which the accounts receivable and accounts payable are

posted, or this may also indicate an accounted portion in the "General ledger," as will hereinafter appear.

At the bottom of the sheet there is provided a horizontal division 22 for containing the "Dr." and "Cr." totals, and entitled "Totals" as at 23, while the major columns from "Cash" to "Expense" are numbered as at 24, these numbers referring to the general ledger folios, the division 25 containing these numbers being entitled "General ledger folios", as at 26.

In Fig. 2, I have shown a sample page of the "Accounts receivable ledger". Each folio is numbered as at 28, and is headed with the name of the creditor as at 29. "Date", "Items", "Folio", "Dr.", "Cr." and "Balance" columns are provided, headed as at 30.

The "Accounts payable ledger" is similar in form, and each folio is numbered as at 31 and headed with the creditor's name as at 32.

In Fig. 4, I have illustrated the "General ledger" sheet 32. This is divided into a plurality of sections headed "Cash", "Bank" etc., as at 33, corresponding to the respective major columns of the "Cash journal".

Each section or folio of the general ledger is numbered as at 34, and is adapted to contain the date as at 35 and 36, and the monthly totals of the "Dr." and "Cr." columns as at 37 and 38.

The operation of my improved system is as follows: In order to clearly illustrate the same, I have shown the instance of a man starting in business with an investment of \$10,000, and the entries are for business done during the first month of the business. Each transaction is first written in detail upon a voucher 43, such as shown in Figs. 5 and 6, voucher No. 1 showing that A. B. Smith has on June 1st engaged in the flour business, investing \$10,000, \$9,900 of which is deposited in the bank and \$100 is placed in the drawer for petty cash. This transaction is placed on the control sheet or "Cash journal" by placing the voucher No. and date in the right hand voucher column, and under "Journal entries", placing in the "Dr." column "Cash", "Bank" and in the "Cr." column "Capital". The respective amounts \$100, \$9,900, and \$10,000 are then placed in the "Dr." and "Cr." columns respectively of the major column, headed "Cash", "Bank" and "Capital and investment", so that the debtor amount balances the creditor amount. This transaction is also posted in the "General ledger" so that J. B. Smith's name is written in the "Cr." column of the "Ledger postings" and is identified by the number "60", this being the number of the "General ledger folio".

The next transaction is for a cash register purchased for \$225. (See voucher Fig. 6).

This is paid for by check and the entries "Furniture", and "Bank" are made in the "Dr." and "Cr." columns under "Journal entries", while the amount \$225 is entered under the "Dr." and "Cr." sections of the "Furniture and fixtures" and the "Bank" columns respectively. The next item is for furniture bought of Bauman Co. for \$160.50, and charged. This transaction is posted in the "Accounts payable ledger" so that it is entered under the "Cr." column of "Ledger postings". Voucher No. 5 represents merchandise bought and paid for by check, a discount of \$11.39 being allowed. The next entry No. 6 is an account receivable, and so on each transaction is entered from the voucher upon the "Cash journal", the amount being entered in a "Dr." and a "Cr." column to balance, and accounts payable and receivable are posted.

At the end of the month the columns are totaled, and the amounts are entered in the "General ledger", the folios being identified by the number 24 at the bottom of the sheet.

The totals of all of the "Dr." and "Cr." columns, respectively, should balance, and should this not be so the mistake may be quickly and accurately traced on the "Cash journal". The condition of the business, the amount of money on hand, paid out and so forth, can be quickly seen at any time during the month, and the balancing of books, paying bills, sending out bills, etc. at the end of the month is greatly simplified.

In Fig. 7, I have shown a trial balance. The balances after subtracting the "Dr." from the "Cr." totals, or vice versa, are added under "Dr." and "Cr." respectively, and should balance. It will be understood that the system may be readily adapted to different businesses by varying the headings of the columns if desired.

I have illustrated a preferred and satisfactory embodiment of my invention, but it is obvious that changes may be made therein within the spirit and scope thereof, as defined in the appended claims.

I claim:

1. In a bookkeeping system, a control sheet provided with a plurality of major columns and horizontal divisions, each of said divisions adapted to receive a record of a transaction, one of said major columns being appropriately designated for journal entries, other of said major columns being appropriately designated for various accounts or classes of accounts, debtor and creditor columns in said major columns, the amount of each transaction adapted to be entered twice to balance in the same horizontal division in said debtor and creditor columns respectively of said last named major columns, said column designated journal entries adapted to receive entries in its respec-

tive debtor and creditor columns to designate the debtor and creditor columns of entry of each transaction.

2. The combination in a bookkeeping system, of consecutively numbered vouchers, each adapted to contain a detailed record of a transaction, a control sheet provided with a plurality of major columns and horizontal divisions, said divisions being numbered to correspond to said vouchers, one of said major columns being appropriately designated for journal entries, other of said major columns being appropriately designated for various accounts or classes of accounts, debtor and creditor columns in said major columns, the amount of each transaction adapted to be entered twice to balance in the same horizontal division in said debtor and creditor columns respectively of said last named major columns, said column designated journal entries adapted to receive entries in its respective debtor and creditor columns to designate the debtor and creditor columns of entry of each transaction.
3. The combination in a bookkeeping system, of consecutively numbered vouchers, each adapted to contain a detailed record of a transaction, an accounts payable ledger, an accounts receivable ledger, a control sheet provided with a plurality of major columns and horizontal divisions, said divisions being numbered to correspond to said vouchers, one of said major columns being appropriately designated for journal entries, another of said major columns being appropriately designated for ledger postings, other of said major columns being appropriately designated for various accounts or classes of accounts, said major columns being divided into debtor and creditor columns, the amount of each transaction adapted to be entered to balance in debtor and creditor columns respectively of said last named major columns, said column designated journal entries adapted to receive entries in its respective debtor and creditor columns, to designate the debtor and creditor columns

of entry of each transaction, said major column designated ledger postings adapted to receive records respectively in its debtor and creditor divisions of accounts receivable and accounts payable, said accounts receivable and accounts payable adapted to be respectively posted in said accounts receivable ledger and said accounts payable ledger, said postings and said records in said column designated ledger postings having corresponding identifying indicia.

4. The combination in a bookkeeping system, of a general ledger, a control sheet provided with a plurality of major columns and horizontal divisions, each of said divisions adapted to receive a record of a transaction, one of said major columns being appropriately designated for journal entries, other of said major columns being appropriately designated for various accounts or classes of accounts, debtor and creditor columns in said major columns, the amount of each transaction adapted to be entered twice to balance in the same horizontal division in said debtor and creditor columns respectively of said last named major columns, said column designated journal entries adapted to receive entries in its respective debtor and creditor columns to designate the debtor and creditor columns of entry of each transaction, a "total" division adapted to receive periodic totals of said entries in said debtor and creditor columns, said debtor and creditor totals of each of said major columns designated for various accounts adapted to be entered in said general ledger, said entries in said general ledger and said last mentioned major columns having corresponding identifying indicia.

In testimony that I claim the foregoing as my invention, I have signed my name in presence of two subscribing witnesses.
